UNITED STATES PATENT OFFICE

MERTON L. EMERSON, OF SYRACUSE, NEW YORK, ASSIGNOR TO THE LAMSON COMPANY,
OF SYRACUSE, NEW YORK, A CORPORATION OF MASSACHUSETTS

PNEUMATIC DISPATCH SYSTEM

Application filed August 2, 1929. Serial No. 382,876.

This invention relates to an improvement in a pneumatic dispatch system, and more particularly in a system of the single transmission tube type wherein the carrier may be sent in one direction through the tube by positive pressure and in the opposite direction through the tube by negative pressure or vacuum.

The primary object of this invention is to provide a system of the single transmission tube type shown in the patent to Fordyce No. 873,531, dated December 10, 1907, and the patent to Maclareen No. 1,396,449, dated November 8, 1921, but differing therefrom in certain features and details of structure whereby the operation of the system is made more accurate and practically automatic.

A further object of the invention is to provide in the system means normally maintaining a minimum flow of air through the transmission tube and responsive to a reduction in such flow, resulting from the insertion of a carrier in the tube, for initiating a carrier impelling flow through the tube and means for initiating a carrier impelling flow through the tube in the opposite direction.

Another object of the invention is to provide in the system a valve which normally permits the maintenance of the minimum flow but which cuts off such flow upon the initiation of the carrier impelling flow in the direction opposite to that of the minimum flow.

Other objects of the invention will be apparent to one skilled in the art from an examination of the following specification wherein one embodiment thereof is described and of the drawings which form a part thereof, and in which

Fig. 1 is a view more or less diagrammatic, illustrating one embodiment of my invention in a pneumatic dispatch system;

Figs. 2 and 3 are sectional views, on an enlarged scale, of the valve construction, Fig. 2 illustrating the valve in its normal position as when a minimum flow is being maintained when a carrier impelling flow by negative or suction pressure is being created, and Fig. 3 illustrating the valve in the posi-

tion it occupies when a carrier impelling flow by positive pressure is being created.

Fig. 4 is a sectional view taken along the line 4—4 of Fig. 2;

Fig. 5 is a sectional view illustrating a portion of the negative pressure tube and the power control therefor;

Fig. 6 is a side elevation illustrating a portion of the positive pressure tube and the power control therefor;

Fig. 7 is a sectional view similar to Fig. 5 of the pressure power control;

Fig. 8 is a plan view taken along the line 8—8 of Fig. 7;

Fig. 9 is a side elevation of the pressure power control unit;

Fig. 10 is an enlarged sectional view of the manually operated actuator for the pressure power control and by which a carrier impelling flow in the tube by positive pressure is initiated;

Fig. 11 is an enlarged sectional view taken along the line 11—11 of Fig. 1 of the central station door and latch;

Fig. 12 is an elevation of the latch shown in Fig. 11 taken in the direction of the arrow 12.

The system illustrated in Fig. 1 comprises briefly a central station A, a substation B, a pressure blower C, and a vacuum blower D. Connecting the stations A and B is a transmission tube 20 terminating at the substation B in an open carrier discharging outlet 21 and an open carrier receiving inlet 22. Located below the outlet 21 is a carrier basket 23, shown as supported upon a platform 24. Leading to the central station A is an air conduit 25 connected by air tubes 26, 27 to drums 28 and 29 respectively. Positive pressure is maintained in the drum 28 by the pressure blower C and negative pressure is maintained in the drum 29 by the vacuum blower D. The air tube 27 is provided with a vacuum time-off power control 30 and the tube 26 is provided with a pressure time-off power control 31.

The tubes 26 and 27 are joined to conduit 25 by a coupling which, in the illustrative embodiment, comprises a T-shaped casing 32 made up of two sections 33, 34 having ob-

liquely faced abutting surfaces. Mounted within the casing 32 is a valve mechanism 35 which is shown in detail in Figs. 2 and 3. The sections 33 and 34, which receive the tubes 26 and 27, are provided with inclined seats 36 and 37, respectively, with which engage a flapper valve 38 mounted upon a shaft 39 supported in a recess 40 formed in the section 34 of the casing. A spring 41 on the shaft 39 normally holds the valve 38 in contact with the seat 36, as shown in Fig. 2. Mounted upon the shaft 39 is an arm 42 carrying at its outer end a plate valve 43 which normally closes an orifice 44 formed in the section 34. When however the valve 38 leaves the seat 36, the arm 42 and valve 43 open the orifice 44 thus providing a free escape to the atmosphere of the air in the tube 27.

The vacuum time-off power control 30 may 20 be of any desired type, and I have elected to show here the type set forth in the copending application of James T. Cowley, Serial No. 317,857, filed November 7, 1928 now Patent No. 1,740,500. This control (see Fig. 5) comprises a casing 50 inserted between and providing a passage in alignment with two sections of the tube 27. Supported in the casing is a shaft 51 extending transversely of the passage upon which is carried a valve 30 52 preferably of the butterfly type by which the passage in the casing is controlled. At one side of the casing 50 is provided a housing 53 consisting of sections 54, 55 between the edges of which a diaphragm 56 is 35 clamped. The diaphragm divides the space within the housing into chambers 57 and 58, the latter being open to the atmosphere through a port 59. The chamber 57 normally communicates with the passage through 40 the casing 50 by a port 60 and communicates with the atmosphere through a bleed passage 61, the size of which is adjusted by a screw 62. When the valve 52 is closed, as shown in the drawings, a certain small but continuous 45 flow of air, commonly known as the minimum flow, is permitted to by-pass the valve through a port 63, the size of which may be adjusted by a screw 64 having a knurled head which is engaged by a spring detent 65. Clamped to the center of the diaphragm 56 is a rod or stem member 66 guided to slide in aligned apertures in the walls of the casing 50 and the housing 53. A lever 67 normally bears against the head 68 of the rod 66, 55 being held in that position by a spring 69. In the lower wing 52^a of the valve 52 is provided an opening 70 through which the rod 66 passes freely. The rod 66 is preferably made in two sections the section 66^a which passes 60 through the opening 70 being smaller in diameter than the section 66^b which is secured to the diaphragm thus providing a shoulder 71 at one side of the valve. On the section 66^a at the other side of the valve is 65 secured a collar 72.

The port 60 is controlled by a valve 75 mounted at one end of a sliding valve stem 76, which extends transversely of the casing 50, its outer end passing through an auxiliary diaphragm 77. The diaphragm 77 is mounted in a housing 78 made up of two parts 79, 80 between the edges of which the diaphragm is clamped and divides the space within the housing 78 into chambers 81, 82. The chamber 82 is in communication at all times with the atmosphere through a port 83, and the chamber 81 is connected to the passage in the casing by ducts 84. Clamped at the center of the diaphragm 77 is a sleeve 85 within which the stem 76 slides freely. The portion 86 of the stem extending through the sleeve 85 is preferably of a smaller diameter than the remainder of the stem, thus providing a shoulder 87 which abuts the inner end of the sleeve 85. At the outer end of the stem 76 are adjustably secured nuts 88 with which the outer end of the sleeve may abut. The ducts 84 are sealed from the atmosphere by a valve plate 89 carried at the end of the rod 66. The operation of the power control 30 will be described briefly hereinbelow.

The pressure power control 31 shown particularly in Figs. 6 to 9 inclusive comprises a casing 90 having a passage therethrough at one side of which is provided a housing 91 which, like the housing 53, consists of two parts 92, 93 between the edges of which are clamped the periphery of a diaphragm 94. The diaphragm 94 divides the housing into two chambers 95 and 96 which are connected 100 at all times through a by-pass 97 controlled by a pin 98. The chamber 95 opens directly into the passage of the casing 90.

Extending transversely across the passage through the casing 90 in an inclined direction 105 is a partition 100 having a central opening 101 therethrough. The opening 101 is normally closed by a valve 102 mounted upon a hinge plate 103 carried by a shaft 104 which extends transversely of the casing 90. A spring 105 normally acts upon the shaft 104 to hold the valve 102 in the closed position shown in Fig. 7. The hinge plate 103 is connected to a stud 106 fixed at the center of the diaphragm 94 by a link 107 which has a pivotal lost motion connection to the plate and stud. Fixed upon the shaft 104 is a dog 108 having an inclined surface 108^a which contacts with the raised edge 109 of the hinge plate 103 and insures the proper location of 110 the valve 102.

Mounted on the part 93 of the housing 91 is a small housing 110 having a chamber 111 therein closed by a hood 112. Clamped between the edges of the hood 112 and the housing 110 is a diaphragm 113 which separates the chamber 111 from the chamber 114 in the hood. To the underside of the diaphragm 113 is secured a plunger 115 which reciprocates freely within the chamber 111. The 125

chamber 111 has an extension 111^a therefrom and the plunger 115 includes a weight 116^a which enters the chamber 111 and a weight 116^b which enters the extension 111^a. The extension 111^a is open to the atmosphere through a port 117 and is connected to the chamber 96 of the housing 91 through a passage 118. The plunger 115 terminates in a tapered valve 119 which in one position closes the port 117. The chamber 114 in the hood 112 is connected by a conduit 120 to the passage 118 and thence to the chamber extension 111^a and the chamber 96, whereby the pressure on either side of the diaphragm 113 is equalized.

In the wall of the part 93 are formed a plurality of bosses 121 and an aperture 122 which is in alignment with the center of the diaphragm 94 and through which projects a sleeve 123 carried by the housing 110. Mounted to reciprocate freely in the sleeve 123 is a pin 124, the outer end of which may be engaged by a latch 125 pivotally mounted on a shaft 126 and normally held in the engaging position by the spring 127. When in the position shown in Fig. 7, the latch 125 bears against the tip of the plunger 115 and holds the valve 119 raised so that the port 117 is open. It will be noted that in this position the inner end of the pin 124 projects beyond the tips of the bosses 121.

Connected to the hood 112 of the housing 110 is a tube 130 which extends to a manually operated member or vent valve 131 preferably located adjacent the central station A. The member 131 (see Fig. 10) comprises a housing 132 having a chamber 133 therein and a cap 134 having a chamber 135 therein. The chambers 133 and 135 are separated by a diaphragm 136, the periphery of which is clamped between the edges of the casing 132 and cap 134. Carried by the diaphragm 136 is a stem 137 which extends through an aperture 138 in the cap 134 and terminates in a button 139. In the casing 132 is a second chamber 140 separated from the chamber 133 by a partition 141 having an aperture 142 therein. The chambers 133 and 140 are each open to the atmosphere through ports 143 and 144 respectively. Secured to the lower end of the casing 132 by threading or otherwise is a cup 145, the center 146 of which is connected to the chamber 140 through a port 147 and through the nipple 148 with the tube 130 and thence with the chamber 114 in the hood 112 of the small diaphragm housing 110. Carried by the diaphragm 136 is a rod 150 which may be integral with the stem 137 or separate therefrom. The rod 150 extends through the chamber 133, the aperture 142 and the chamber 140 and carries at its lower end a disk valve 151 which may close the port 147. A spring 152 encircling the rod 150 normally raises

the valve 151 and thereby yieldingly seals the port.

Mounted in the upper end of the passage through the casing 90 is a butterfly valve 155 mounted upon a shaft 156. Fixed on one end of the shaft 156 (see Fig. 6) is a locking plate 157 having a slot 158 therein. A set screw 159 passes through the slot 157 into engagement with the casing 90 and thus secures the valve in the proper position in the passage to insure pressure of the amount desired.

The central station comprises a box or receptacle 160 into which enter one end of the transmission tube 20 and one end of the conduit 25. The box 160 is sealed and thus its interior acts as a connecting passage between the tube and the conduit. The box has an opening in its side closed by a door 161 hinged upon a shaft 162 and provided with a latch 163. A spring 164 acts to hold the door normally closed. The latch 163 comprises a shank 165 rotatably supported in a body 166 fixed to the inner face of the door 161. Secured to the inner end of the shank is a latch plate 167 and a flat spring 168. The plate and spring are secured to the shank by a screw 169. The inner end of the shank is faced off as indicated in dotted lines in Figs. 11 and 12 so that it has a positive engagement with the plate 167. A pin 170 holds the spring in position on the plate and a stop 171 limits the movement of the latch plate in either direction. Packing 172 at the inner edge of the door makes the box air-tight when the door is closed.

It will be understood that the pressure blower C and the vacuum blower D are in operation at all times, keeping their respective drums 28 and 29 in the proper condition. The valve 38 is normally in the position shown in Fig. 2 so that the vacuum blower D is in direct connection with the air tube 25 and through the box 160 with the carrier tube 20. The vacuum power control 30 is normally in the position shown in Fig. 5 whereby a minimum flow of air is maintained in the transmission tube. The pressure blower C is also in operation and by reason of the by-pass 97 the diaphragm 94 is held in a position shown in Fig. 7 with the opening 101 closed by the valve 102. The door 161 of the box is locked and the button 139 of the vent valve 130 is in its normal position.

If a carrier is to be sent from substation B to central station A, it is inserted into the cutlet 22. The reduction of the minimum flow by the insertion of the carrier causes the control 30 to function in the manner set forth in the copending Cowley application which is briefly to close the port 60 by the action of the diaphragm 77 and open the valve 52 by the action of the diaphragm 56, thus furnishing a free passage to the vacuum drum and initiating a carrier impelling flow in the tube

20 in the same direction as the minimum flow. The carrier is thus impelled to the central station A and when ejected from the tube 20 the flow is again reduced to the minimum and the parts return to the position shown.

5 If on the other hand a carrier is to be sent from the central station A to the substation B, the door 161 is opened and the carrier placed in the mouth of the tube 20. The 10 door 161 is then closed and secured by the latch 163 and the button 139 depressed. The depression of the button 139 causes the valve 151 to open the port 147 and allow through the tube 130 a free connection to the atmosphere of the chamber 114 in the auxiliary housing 110. This upsets the equilibrium in the housing and causes the diaphragm 113 to rise, whereupon the plunger 115 lifts the valve 119, opening the port 117. The tip of the plunger is raised above the latch plate 125 which, under the urge of the spring 127, swings into the position shown in Fig. 7 and prevents the depression of the plunger 115. The equilibrium in the main housing 91 is 25 similarly upset by the fact that the air can escape from the chamber 96 through the passage 118 and conduit 120 into the chamber 114 and thence to the atmosphere and can also escape through the port 117. The diaphragm 94 under the pressure in the drum 28 will then swing into the dotted line position shown in Fig. 7, resting against the bosses 121 and the valve 102 will be opened, allowing the air to pass through the casing 90 toward the 30 conduit 25. This rush of air swings the valve 38 from the position shown in Fig. 2 into that shown in Fig. 3 and allows the air under positive pressure to enter the conduit 25 freely. A carrier impelling flow is thus 35 initiated in the tube 20 and the carrier impelled to the station B.

40 As the diaphragm 94 takes the dotted line position of Fig. 7, it bears against the end 128 of the pin 124 and swings the latch 125 out of engagement with the tip of the plunger so that the latter will descend by reason of the weights thereon. The button 139 is in the meantime released after there has been introduced an amount of air under pressure 45 slightly more than that necessary to cause the carrier to complete its journey. The rod 150 then returns to its normal position, under the urge of the spring 152, closing the port 147 and thus breaking the connection of the chamber 114 to the atmosphere through the tube 130. The pressure in the chamber 96 will then build up until the diaphragm 94 returns to its normal position closing the opening 101 and cutting off the supply of air 50 under pressure to the conduit 26 and transmission tube 20. The valve 38 will return to its normal position as soon as the supply of air under positive pressure is cut off.

55 It will be noted that when the carrier impelling flow is being created in the tube 20

60 by positive pressure and the valve 38 is bearing against the seat 37 as in Fig. 3, the valve 43 will open the port 44, thus permitting the entry of air from the atmosphere to prevent building up the vacuum in the tube 27 which 65 would cause the control 30 to operate unnecessarily.

70 While certain features of the selected embodiment have been shown and described in detail, it will be understood that I am not 75 limited to such features per se and that my invention covers any substitutions or equivalents that come within the spirit and scope of my invention as set forth in the following 80 claims.

I claim:

1. In a pneumatic dispatch system, two stations, a single transmission tube connecting said stations, means normally maintaining a minimum flow of air through the tube, and responsive to a reduction in such flow resulting from the insertion of a carrier in the tube, for initiating a carrier impelling flow through the tube in one direction at least and means for terminating said minimum flow and initiating a carrier impelling flow through the tube in the opposite direction.

2. In a pneumatic dispatch system, two stations, a single transmission tube connecting said stations, means normally maintaining a minimum flow of air through the tube, and responsive to a reduction in such flow resulting from the insertion of a carrier in the tube, for initiating a carrier impelling flow through the tube in one direction at 100 least and manually controlled means for terminating said minimum flow and initiating a carrier impelling flow through the tube in the opposite direction.

3. In a pneumatic dispatch system, two stations, a single transmission tube connecting said stations, means normally maintaining a minimum flow of air through the tube and manually controlled means for terminating said minimum flow and initiating a carrier 110 impelling flow through the tube in the direction opposite to that of the minimum flow.

4. In a pneumatic dispatch system, two stations, a single transmission tube connecting said stations, means normally maintaining a minimum flow of air through the tube and means for terminating said minimum flow and initiating a carrier impelling flow through the tube in the direction opposite to that of the minimum flow.

5. In a pneumatic dispatch system, two stations, a single transmission tube connecting said stations, means normally maintaining a minimum flow of air through the tube, said means including a valve and means for shifting the position of the valve thereby terminating the minimum flow and for initiating a carrier impelling flow through the tube in one direction at least.

6. In a pneumatic dispatch system, two

- stations, a single transmission tube connecting said stations, means normally maintaining a minimum flow of air through the tube, said means including a valve and manually controlled means for shifting the position of the valve thereby terminating the minimum flow and for initiating a carrier impelling flow through the tube in one direction at least. 5
- 16 7. In a pneumatic dispatch system, two stations, a single transmission tube connecting said stations, means normally maintaining a minimum flow of air through the tube, said means including a valve and manually controlled means for shifting the position of the valve thereby terminating the minimum flow and for initiating a carrier impelling flow through the tube in the direction opposite to that of the minimum flow. 15
- 16 8. In a pneumatic dispatch system, two stations, a single transmission tube connecting said stations, means normally maintaining a minimum flow of air through the tube, said means including a valve and means for shifting the position of the valve thereby terminating the minimum flow and for initiating a carrier impelling flow through the tube in the direction opposite to that of the minimum flow. 25
- 23 9. In a pneumatic dispatch system, two stations, a single transmission tube connecting said stations, means normally maintaining a minimum flow of air through the tube said means including a valve, means, responsive to a reduction in such flow resulting from the insertion of a carrier in the tube, for initiating a carrier impelling flow in one direction and manually operable means for shifting the position of the valve thereby terminating the minimum flow and preventing the operation of the reduction responsive means and for initiating a carrier impelling flow through the tube in the opposite direction. 35
- 45 10. In a pneumatic dispatch system, two stations, a single transmission tube connecting said stations, one of said stations including a box in which one end of the tube terminates, a conduit leading from the box, a source of negative air pressure, a source of positive air pressure, tubes connecting said sources with the conduit, a valve at the junction of said tubes and conduit normally closing the tube from the source of positive air pressure, the tube from the source of negative air pressure having an opening therein, a valve normally closing said opening, a power control for initiating a carrier impelling flow through the transmission tube in one direction upon the insertion of a carrier therein and a manually operable power control for shifting said valves from their normal position and initiating a carrier impelling flow through the transmission tube in the other direction. 55
11. In a pneumatic dispatch system, two stations, a single transmission tube connecting said stations, one of said stations including a box in which one end of the tube terminates, a conduit leading from the box, a source of negative air pressure, a source of positive air pressure, tubes connecting said sources with the conduit, a valve at the junction of said tubes and conduit normally closing the tube from the source of positive air pressure, the tube from the source of negative air pressure having an opening therein, a valve normally closing said opening, a power control associated with the source of negative air pressure for initiating a carrier impelling flow through the transmission tube in one direction upon the insertion of a carrier therein and a manually operable power control associated with the source of positive air pressure for shifting said valves from their normal position terminating the carrier impelling flow above mentioned and initiating a carrier impelling flow through the transmission tube in the opposite direction. 70
12. In a pneumatic dispatch system, two stations, a single transmission tube connecting said stations, one of said stations including a box in which one end of the tube terminates, a conduit leading from the box, a source of negative air pressure, a source of positive air pressure, tubes connecting said sources with the conduit, a valve at the junction of said tubes and conduit normally closing the tube from the source of positive air pressure, the tube from the source of negative air pressure having an opening therein, a valve normally closing said opening, a power control associated with the source of negative air pressure for normally maintaining a minimum flow of air through the transmission tube and responsive to a reduction in such flow resulting from the insertion of a carrier in such tube at one station, for initiating a carrier impelling flow through the tube toward the other station and a manually operable power control for shifting said valves from their normal positions and initiating a carrier impelling flow through the tube in the opposite direction. 80
13. In a pneumatic dispatch system, two stations, a single transmission tube connecting said stations, one of said stations including a box in which one end of the tube terminates, a conduit leading from the box, a source of negative air pressure, a source of positive air pressure, tubes connecting said sources with the conduit, a valve at the junction of said tubes and conduit normally closing the tube from the source of positive air pressure, the tube from the source of negative air pressure having an opening therein, a valve normally closing said opening, and means for shifting said valves out of their normal positions thus opening the tube from the source of positive air pressure and closing 85

the tube from the source of negative air pressure and uncovering the opening.

14. In a pneumatic dispatch system, two stations, a single transmission tube connecting said stations, one of said stations including a box in which one end of the tube terminates, a conduit leading from the box, a source of negative air pressure, a source of positive air pressure, tubes connecting said sources with the conduit, a valve at the junction of said tubes and conduit normally closing the tube from the source of positive air pressure, the tube from the source of negative air pressure having an opening therein, a valve normally closing said opening, said valves being joined to move as a unit and means for shifting the first mentioned valve to open the tube from the source of positive air pressure and close the tube from the source of negative air pressure, such movement causing the second valve to uncover the opening.

Signed by me at Syracuse, New York, this thirty-first day of July, 1928.

MERTON L. EMERSON.
